UNITED STATES PATENT OFFICE.

WENZESLAW FRANK SKLENAR, OF LONDON, ENGLAND.

REVERBERATORY FURNACE.

Application filed October 3, 1921. Serial No. 505,180.

To all whom it may concern:

Be it known that I, WENZESLAW FRANK SKLENAR, a subject of Czechoslovakia, residing at 5, Caldervale Road, Clapham Common, London, England, have invented a new or improved Reverberatory Furnace of which the following is a specification.

This invention relates to a new or improved reverberatory furnace of the fusion or melting type and has for its primary object the production of a highly efficient furnace which may in some cases be readily moved from place to place as required, is inexpensive to construct, and operate, and is economical in fuel.

The present invention consists of a reverberatory air blast furnace and comprises essentially a metal casing, a carriage or frame supporting said casing, and in some cases wheels carried by the carriage or frame adapting it to be moved from place to place, preferably on rails, a lining of fire bricks so arranged and held within said casing as to form a working bed with vaulted roof, a combustion chamber or fire place, a fire bridge and an up take or hopper at the opposite end to the fire place in communication with the working chamber by a restricted passage, an inlet for compressed air situated beneath the fire bars, which are removable, charging holes in the roof for fuel and metal and inspection and tapping holes in the side wall.

By the introduction of an air blast in a reverberatory melting furnace, the time required for bringing the metal to a casting temperature is much reduced and an economy of fuel is obtained by the more perfect combustion resulting from a forced draught.

The improved furnace which may be used for melting all metals and alloys but is more particularly applicable for melting copper alloys and has marked advantages over the more usual method of employing pot or crucible furnaces and owing to the greater heat obtainable in less time than with the usual furnaces employed for melting copper alloys, it is practicable to obtain better results in a more economical manner, as since the metal is not exposed to such an extended heating period in its molten or semi-molten condition, the more easily oxidizable metals—for instance the spelter in brasses—are not volatilized to such an extent, moreover with certain copper alloys it is usual to

add an excess of one of the metals to obtain a freely running metal at a lower temperature, for instance in casting phosphor bronze, it is usual to add an excess of phosphor copper—which is the most expensive of the alloying metals—in order to obtain an alloy sufficiently fluid for casting at the temperature obtainable in a pot or crucible furnace.

A further advantage of the present invention is that an uninterrupted succession of charges can be melted or practically a continuous working of the improved furnace, is possible thereby resulting in a great economy of fuel and—when furnished with wheels—owing to it being possible to readily move the furnace from place to place during operation, it may be brought into proper position for pouring into the moulds without having first to run the molten metal into a ladle, thus effecting economy in time and labour.

It will also be appreciated that by making it possible to dispense with a chimney as is necessary with existing furnaces, the first cost of the furnace is very materially reduced.

In the accompanying drawing illustrating this invention:

Fig. 1 is a view in side elevation of the improved reverberatory furnace.

Fig. 2 is a similar view thereof in longitudinal section.

Fig. 3 is a transverse section on line A—A of Fig. 2, and

Fig. 4 is a sectional plan view.

Throughout the views similar parts are marked with like letters of reference.

A suitably shaped metal casing *a*, preferably formed of angle iron and metal plates rivetted together, is mounted on an under frame *b* which is provided with wheels *c* adapting the entire furnace to be readily moved from place to place, preferably on rails *d*.

The metal casing *a* is furnished with an interior lining of fire clay, ganister, or preferably fire bricks as shown so arranged or built up as to provide a vaulted roof *a*¹ and a curved working bed *a*² which also slopes transversely (see Fig. 3) the arrangement being such that the lowest point of the bed is opposite the tapping hole or duct *e* in the side wall. At the back end of the bed *a*² is formed the combustion chamber or fire place *a*³ and between the two is formed

the usual fire bridge a^4 . The top of this bridge is provided with bricks set on edge and a distance apart so as to form passages for the better distribution of the hot gases over the metal. Within the lower part of the chamber a^3 are arranged longitudinal bearers f over which are placed transverse fire bars f^1 . This arrangement allows for fire bars being readily adjusted and renewed.

10 At the opposite end of the furnace to the chamber a^3 is formed a short vertical up take or hopper a^5 which is in communication with the working chamber by a restricted passage a^6 . This up take or hopper a^5 serves not only as an exit for the combustion gases but serves also for the introduction of fresh metal into the furnace. A hole a^7 in the roof a^1 immediately above the bed a^2 is also provided for introducing fresh

15 metal—for instance in the form of turnings, filings or the like—into the furnace and is normally closed by a cover a^8 . A hole a^9 is provided in the roof over the combustion chamber a^3 for the introduction of fuel which hole is normally closed by a cover a^{10} .

20 A door a^{11} is provided for giving access to the fire place a^3 and a hole a^{12} preferably situated above the tapping hole or duct e is provided in the side wall to allow of inspecting the interior of the furnace or/and for the introduction of tools or rods for stirring the molten metal on the bed a^2 . On the opposite side wall to that of the door a^{11} and entering the combustion chamber a^3 or fire place a^3 is a pipe or inlet g for the introduction of an air blast or a volume of compressed air from any suitable source.

25 In a modification particularly adapted for melting iron and steel scrap, the up take or

hopper a^5 may be inclined instead of vertical as shown so as to allow an easier path for the escape of products of combustion.

I claim:—

1. A reverberatory melting furnace comprising a metal casing, a frame supporting said casing, a lining of fire bricks arranged within said casing to form (1) a working bed with vaulted roof constituting a working chamber (2) an enclosed combustion chamber or fire place (3) a fire bridge (4) an up take and metal feeding hopper at the opposite end to the fire place, and (5) a restricted passage forming a communication between said hopper and the working chamber, an inlet for compressed air opening into the combustion chamber beneath the fire bars of the grate, charging holes in the roof for fuel and metal and inspection and tapping holes in the side wall, as set forth.

2. A reverberatory melting furnace comprising a metal casing, a frame supporting said casing, wheels carried by said frame adapting it to be readily transported, a lining of fire bricks arranged within said casing to form (1) a working bed with vaulted roof constituting a working chamber (2) an enclosed combustion chamber or fire place (3) a fire bridge (4) an up take and metal feeding hopper at the opposite end to the fire place, and (5) a restricted passage forming a communication between the hopper and the working chamber, an inlet for compressed air opening into the combustion chamber beneath the fire bars of the grate, charging holes in the roof for fuel and metal and inspection and tapping holes in the side wall, as set forth.

WENZESLAW FRANK SKLENAR.
